UNITED STATES PATENT OFFICE.

JOHN D. BRUNNER, OF DOYLESTOWN, PENNSYLVANIA.

IMPROVEMENT IN GRAIN-SEPARATORS.

Specification forming part of Letters Patent No. 116,549, dated July 4, 1871; antedated June 22, 1871.

To all whom it may concern:

Be it known that I, JOHN D. BRUNNER, of Doylestown, in the county of Bucks and in the State of Pennsylvania, have invented certain new and useful Improvements in Grain-Separator; and do hereby declare that the following is a full, clear, and exact description thereof, reference being had to the accompanying drawing and to the letters of reference marked thereon making part of this specification.

The nature of my invention consists in the construction and arrangement of a grain-separator, as will be hereinafter more fully set forth.

In order to enable others skilled in the art to which my invention appertains to make and use the same, I will now proceed to describe its construction and operation, referring to the annexed drawing, in which—

Figure 1 is a longitudinal vertical section, and Fig. 2 is a plan view of my machine. Fig. 3 is a perspective view of one of the screens in the separator.

A represents the frame of my machine, in the upper rear end of which is the hopper B. This hopper is provided with two openings, a, each having a lid, b, as shown. C is the shoe containing the screens D D', said shoe being suspended at the rear end by straps d d, and resting at or near the front end on a square shaft, E, or rather on a square jog, f, in the middle of the shaft E. On the under side of the shoe C is a projection, g, bearing against the rear side of the jog f, so that, when the shaft E is revolved, by means of a crank at one end, or any other suitable means, the shoe will get two motions, up and down and endwise, which are very necessary to cause the

grain to flow down. The screens D D' are placed in grooves in the sides of the shoe C, and spouts h h arranged at the front end of the shoe, as shown in Fig. 1, carry the grain from said screens into different compartments of the seed-box G. The screens are of different fineness, so as to be used for different seed, and they are arranged so that the grain on two of them flows faster than on the other two. This is accomplished by having two of the screens hung or pivoted at their front ends to cleats k k, which cleats slide in the grooves on the shoe, so that the rear ends of said screens may be raised up. One of these two screens, D', is represented in Fig. 3. By this machine I can take the cockle and cheat all out of wheat, and, at the same time, separate the large grains of wheat from the small, having the large wheat to sow. By the proper arrangement of the four screens I can separate all seeds and grains, if mixed together.

Having thus fully described my invention, what I claim as new and desire to secure by Letters Patent, is—

The combination, in the grain-separator herein described, of the screens D', provided with the cleats k, with the shoe C provided with the lug g and the shaft E, when all these parts are constructed and arranged as shown and described, for the purposes set forth.

In testimony that I claim the foregoing I have hereunto set my hand this 23d day of November, 1870.

JOHN D. BRUNNER.
